UNITED STATES PATENT OFFICE.

CARL EICKEMEYER, OF YONKERS, NEW YORK.

GAS-HEATER.

No. 823,267.

Specification of Letters Patent.

Patented June 12, 1906.

Application filed October 17, 1905. Serial No. 283,118.

To all whom it may concern:

Be it known that I, CARL EICKEMEYER, a citizen of the United States, residing in Yonkers, in the county of Westchester and State 5 of New York; have invented certain new and useful Improvements in Gas - Heaters, of which the following is a specification.

This invention has reference to heaters such as used in living-rooms and the like, and 10 has among its objects to provide a heater in which the gases of combustion are utilized to their fullest extent.

Further objects of the invention are to provide improved means for permitting access of 15 air to the burner without the waste of heat therefrom and also to furnish a construction of heater in which the parts are assembled in such a manner as to be readily taken apart when necessary.

With these and other ends in view the invention consists in a heater embodying the 20 novel features, arrangements, and combinations of parts to be hereinafter described, and finally defined in the claims.

In the accompanying drawings, in which the same parts are designated by corresponding 25 reference characters throughout the several views, Figure 1 is a front elevation of a heater constructed in accordance with the invention. Fig. 2 is a top plan view of the same. Fig. 2^a is a detail perspective view showing the exhaust-compartment in the upper heat-box, the upper portion of the latter being removed. Fig. 2^b is a vertical trans- 30 verse section through the upper heat-box, taken on line 2^b 2^b, Fig. 2. Fig. 3 is a vertical longitudinal section taken on line 3 3 of Fig. 2. Fig. 4 is a vertical longitudinal section through the lower and upper plates of 35 the upper and lower heat-boxes, respectively. Fig. 5 is a top plan view of the heater having the upper portion or cover of the upper heat-box removed, and Fig. 6 is a detail section 40 showing the heat-fender plate below the burner and the manner of mounting said plate.

Referring to the drawings, *a* *b* denote upper and lower heat-boxes, between which extend a number of radiator-tubes *c* and at one 45 end a larger burner-tube *d*. The lower heat-box *b* is provided with suitable legs upon which the heater is supported. It will be seen that the lower heat-box *b* is made in superposed sections, the lower section *e* forming the main part of said box, while the upper section *f* constitutes the cover thereof. The

cover or plate *f* is provided with a number of circular apertures *f'*, arranged in two longitudinally-extending rows, and said apertures are provided with marginal seats, in which 60 rest the lower ends of the radiator tubes or elements *c*. At one end the section *f* is provided with a comparatively large circular aperture *f''*, surrounded by a flange *g*, which is embraced by and forms a seat for the lower 65 end of the burner-tube *d*. The sections *e* *f* are firmly clamped together by means of upright bolts *h*, the lower nuts of which form a tight closure and prevent the escape of water 70 through the bolt-holes.

The upper heat-box *a* is constructed similarly to the lower heat-box—that is to say, it is constituted by superposed sections, the relation of which, however, is reversed. The lower section *i* is provided with a large circular opening *i'*, registering with the burner-opening in the lower heat-box and surrounded by a flange *j* similar to the flange *g*. About 75 said flange fits the upper end of the burner-tube *d*. The section or plate *i* is likewise provided with a number of circular apertures *i''*, arranged in longitudinally-extending rows and registering with the openings *f'* in the section *f*, and these apertures are surrounded by downwardly-extending flanges, about 80 which fit the upper ends of the radiator elements *c*. The upper section *v* of the heat-box *a* constitutes the main portion of the same and corresponds with the section *e*, being united with the section *i* by means of 85 bolts *k*, corresponding to the bolts *h* used in interclamping the lower sections. The upper section of the heat-box *a* is provided immediately above the burner-tube or flue *d* with a removable lid *l*, over which may be set 90 cooking utensils and the like, which thus absorb the heat directly from the burner. At the opposite end of the section *a* an exhaust-compartment is provided, from which rises a 95 collar or flange *m* for attachment to the smoke-pipe. Said exhaust compartment or chamber is constituted by upright walls *n*, arranged at right angles to each other in one corner of the box *a*, as shown best in Fig. 2^a.

A burner *o* is arranged in the lower heat-box *b* immediately below the burner-flue *d*, and said burner is supplied with gas by means of pipes *p*, communicating therewith. Immediately below said burner the section *e* of the heat-box *b* is left open in order to permit an upward air-draft; but in order to retain the heat in the burner-tube and prevent 100 105 110

its escape in downward direction a circular fender-plate *q* is arranged beneath said opening, as shown in Fig. 6, being supported by means of a bracket *r*, similar to the bracket *s*, 5 by means of which the burner *o* is supported. Said plate *q* is of substantially the same area as the opening beneath the burner, but is spaced downwardly, so that air can enter at the sides of the same, as indicated by the arrows in Fig. 6.

Both of the heat-boxes *a b* are provided between the rows of radiator elements with a longitudinal row of vertically-disposed air-passages *t*, by means of which the upward passage of the air through said heat-boxes and between the radiator elements is afforded.

The whole structure described is held together firmly by means of bolts u , passing downwardly from the upper heat-box, through several of the radiator elements, and through the lower heat-box, as shown in Fig. 3. The upper end of one of said bolts is supported in a bracket u' , arranged in the exhaust-chamber, as shown in Fig. 2^b.

25 The operation of the improved heater is as follows: The heat being generated in the burner-tube d , which is supplied with air at the sides of the fender-plate g , rises from said tube into the upper heat box or compartment a and is diffused throughout the same.

30 The hot air then passes downwardly through all the elements c and into the lower heat-box b , where it is likewise diffused. Both boxes and all the radiator elements are thus filled

35 with the hot gases of combustion, and substantially the entire surface of the heater radiates heat. A draft is created in the smoke-pipe and the radiator element directly connected thereto, so that the hot gases are

40 sucked downwardly into the lower heat-box and thence upwardly through the radiator element in communication with the exhaust-compartment, which element might be

termed the "exhaust element." After passing upwardly through said exhaust element 4 the gases enter the exhaust-compartment (being prevented from reentering the box *a* by means of the partitions *n*) and pass upwardly into the smoke-pipe, which is connected with the collar *m* and preferably arranged to conduct the gases of combustion from the room, the entrance of said gases into the latter at any point being thus prevented, so that the atmosphere will not be vitiated. 5

Having thus described my invention, I claim as new and desire to secure by Letters Patent—

1. A heater comprising upper and lower heat-boxes, a burner-tube connecting the same, a burner arranged in the lower portion of said burner-tube, a plurality of upright radiator tubes or elements likewise connecting said heat-boxes, and partitions in said upper heat-box forming therein a single exhaust-compartment communicating directly with only one of said elements, the hot gases passing through said last-named element in upward direction, but through the other elements in downward direction. 7c

2. In a heater, the combination of upper and lower heat-boxes, each made in superposed sections, bolts to interclamp the sections of each box, a burner-tube connecting said boxes, radiator-tubes also connecting the same, and bolts passing vertically through the upper heat-box, certain of said radiator-tubes, and the lower heat-box. 75

In testimony that I claim the foregoing as my invention I have signed my name in presence of two subscribing witnesses. 80

CARL EICKEMEYER.
